UNITED STATES PATENT OFFICE

SAMUEL S. MATTHES, OF MANSFIELD, OHIO, ASSIGNOR TO THE OHIO BRASS COMPANY,
OF MANSFIELD, OHIO, A CORPORATION OF NEW JERSEY

CROSSOVER DEVICE

Application filed April 20, 1932. Serial No. 606,351.

My invention relates to crossover devices for use in overhead trolley construction.

One object of my invention is to provide a device which will guide a current collector of either the wheel or shoe type across the intersection of two trolley wires.

Another object of my invention is to provide a crossover which is operated in one direction by the current collector but not in the other.

My invention resides in the new and novel construction, combination and relation of the parts hereinafter described and shown in the accompanying drawing.

In the drawing:—

Fig. 1 is a top view of my invention with its protecting cover removed.

Fig. 2 is a side view of Fig. 1 in partial section with the protecting cover in position.

Fig. 3 is a sectional view on the line 6—6 of Fig. 2.

Fig. 4 is a side view of one of the guide members.

Fig. 5 is an end view of the guide member.

Fig. 6 is a top view of the guide member.

In overhead trolley construction there are points where two trolley wires may intersect or cross and where it is desirable to use the crossing for guiding the movement of the current collector on a moving vehicle across the point of intersection.

In my preferred embodiment I employ a body or pan member 1 which has a top portion 2 which is of substantially flat formation and depending side members 3.

Projecting from the ends of the pan 1 are arms 4—4' and 5—5' each provided with a groove 6 to receive the trolley wires 7—7' and 8—8'.

The side walls of the projecting arms adjacent their outer ends are provided with hook-shaped projections 9 and interlocked therewith are removable tips 10 each provided with an inverted U-shaped groove to receive the trolley wire and having laterally projecting bosses 11 which interlock with the hook-shaped members 9 and a cam-shaped portion to engage the trolley wire positioned in the groove 6 to hold the trolley wire against the lower portion of the groove, thus

tensioning the trolley wire in position with respect to the pan 1 and holding the device in secure engagement with the trolley wires. The tips 10 are provided with thin lip portions 12 which may be bent about the trolley wire after the trolley wire is positioned.

The arms 6 project inwardly toward the center a pre-determined distance beyond the ends of the pan as shown in Fig. 3 and the arms 4—4' project inwardly a greater distance than the arms 5—5'.

The top portion 2 and the side walls 3 of the pan form a trough-like construction having a main portion 13 and offset portions 14 as shown in Fig. 3; the dotted lines 15 indicating the division between what I term the main portion 13 and the offset or recess portion 14.

The top portion 2 is provided with a hollow pedestal 16 adjacent each end and having a passage extending through each pedestal. Pivotal mounted on the pan are two normally aligned guides 17 and each guide is provided with a longitudinal portion 18 and a stem portion 19 connected by the offset portion 20. The stem portion 19 extends into and through the hollow pedestal 16.

The projecting ends of the stems 19 are provided with a lever 21 secured in position by means of the set screw 22 and the outer ends of the levers 21 are pivotally connected to a connecting rod 23 by means of rivets or screws 24. It will be evident that when the rod 23 moves in one longitudinal direction the guides 17 will move out of alignment with each other and if the rod 23 is moved in the other direction the guides 17 will be moved back into alignment. The guides are held normally in an aligned position by means of the spring 25 which is secured to the rod 23 and to one of the levers 21. If the spring 25 were connected to the other lever 21 than that shown in Fig. 1 then the tendency would be to cause the guides 17 to be moved out of alignment and normally held out of alignment.

To reduce arcing at joints and to increase the conductivity of the parts a jumper cable 26 is connected to the pan and to the upper end of each stem 19 by means of the screws

27. The adjacent abutting ends of the guides 17 are beveled as shown in Fig. 3.

When the guides are moved out of their normal position from that shown in Fig. 3 5 they will assume the position shown by dotted lines in Fig. 1 and will rest partially within the offset recess 14. This provides a clear runway for a current collector when passing from trolley wire 7 to trolley wire 10 7' or vice versa.

By referring to Fig. 3 it will be evident that a current collector approaching the device and passing from arm 5 to 5' or vice versa will pass across the guides 17. If the 15 current collector should enter the device by way of the arm 4 such current collector will engage the side wall of the guide 17 nearest the arm 4 and move it out of its normal position to that shown by dotted lines in Fig. 20 1 and simultaneously the opposite guide 17 will be moved out of its normal position as shown by dotted lines in Fig. 1 thus giving the current collector a clear right-of-way across the device.

25. It will be noted that the right-of-way from the arm 4 to the arm 4' or vice versa is formed by the walls 3 and the guides 17. As the current collector approaches the end of its movement across the pan 1 the guides 17 30 will move back to their normal position under action of the spring 25.

The guides 17 are positioned with the vertical axis of the stem 19 positioned between the longitudinal axes of the arms 4-5 and 35 4'-5' and the ends of the guides 17 adjacent the ends of the arms 5 and 5' are grooved.

In order to maintain the operating mechanism as free from snow and ice as possible 40 a cover 28 which may be formed of sheet iron is secured to the body or pan member 1 by means of the bolts 29 which in turn are secured to upright lugs 30.

The portion 2 of the body 1 is provided with an enlarged recessed portion 31 to receive the offset portion 20 of the guide 17 45 thus permitting the lower face of the portion 2 to be substantially free of obstructions.

The guides may be cored out as at 32 if desired to lighten and save metal.

There will be modifications which will suggest themselves to those skilled in the art, therefore, I wish to be limited by my claims only.

55. I claim:—

1. A trolley device comprising a body and a plurality of spaced arms to guide a current collector onto and off of the body, a pair of guides pivotally mounted at their remote ends 60 to the body and arranged to be normally in longitudinal alignment with each other and two of the oppositely disposed arms, means to move the guides in unison with each other upon their pivotal mountings into and out of alignment with each other and the said two 65

arms and yielding means to return the guides to and hold them in their normal positions.

2. A trolley device comprising a body and a plurality of spaced arms to guide a current collector onto and off of the body, a pair of guides pivotally mounted on the body and arranged to be normally in longitudinal alignment with each other and two of the oppositely disposed arms, means to move them in unison upon their pivotal mountings out of and back to their normal position and a spring to return the guides to their normally aligned position when moved out of alignment by a current collector engaging one of the guides when moving across the body in a path angularly disposed to the aligned guides.

3. A trolley device comprising a body member and a plurality of spaced arms projecting from opposite ends thereof and each arranged to receive a trolley wire, a pair of movable guide members pivotally secured to the body and arranged normally in alignment with each other and to bridge the space between the inner ends of two of the oppositely disposed arms to complete a guideway for a current collector, the guide members meeting at their inner ends and pivoted to the body at their outer ends, mechanism to operate the guide members comprising an operating member secured to each guide member to pivot therewith and a connecting member pivotally connecting the operating members to move both guide members simultaneously either into or out of alignment 100 when one guide member is engaged by a moving current collector and exerting a side pressure upon the one guide member and yielding means to return the guide members to normal position when said pressure is removed.

4. A trolley device comprising an elongated body member having an upper plate and a downwardly projecting flange along its side edges to form a main trough and a recess opening into the main trough and a plurality of spaced arms projecting from the said plate adjacent its ends and each arranged to receive a trolley wire, a pair of guide members normally aligned with each other and with two oppositely disposed arms to guide a current collector thereacross, the guide members pivotally mounted on the body to move laterally of the body and the free end of each to move into the recesses 110 to form a channel connecting the inner ends of the arms not connected by the guide members, to guide a current collector across the body.

5. A device of the class described comprising in combination a body, a plurality of spaced means to guide a current collector onto and off of the body, a pair of elongated guide members pivoted to the body adjacent the ends of two of the oppositely disposed spaced 120 130

means, the said guide members and spaced means normally in alignment and means acting on the guide members to yieldingly maintain such alignment and means associated with the guide members to move one of the guide members out of alignment with the adjacent spaced means when the other guide member is engaged by the current collector and moved on its pivot to form a passage to guide the current collector across the device.

6. A device of the class described comprising in combination a body, a plurality of spaced means secured to the body to receive trolley wires and to guide a current collector onto and off of the body, a pair of normally aligned guide members connecting the inner ends of two of the spaced means and pivotally secured to the device at points adjacent the inner ends of the connected spaced means, the inner or adjacent ends of the guide members being movable laterally to separate the said ends and means associated with the guide members to move them simultaneously.

7. A crossing for trolley wires comprising an elongated body of trough-like construction forming a channel extending from end to end of the body and having two sections in offset relation to each other in a lateral direction, a plurality of spaced and projecting means secured to the body to guide a current collector onto and off of the body, two guide members pivoted to the body in aligned relation to each other and to two of the said spaced means, means associated with the guide members to pivot them in unison and out of said aligned relation when one guide member is moved, means to yieldingly hold the guide members normally in alignment.

8. A crossing for trolley wires comprising an elongated body of trough-like construction forming a channel from end to end of the body and having two sections in offset relation to each other in a lateral direction, a plurality of spaced and projecting means secured to the body to guide a current collector onto and off of the body, two guide members pivoted to the body in aligned relation to each other and to two of the said spaced means, means associated with the guide members to pivot them in unison and out of said aligned relation when one guide member is moved, means to yieldingly hold the guide members normally in alignment, the spaced and projecting means arranged to receive the trolley wires and means adjacent the free end of each projecting means to engage the trolley wire and hold it securely to the projecting means.

9. A crossing for trolley wires comprising an elongated body of trough-like construction forming a channel extending from end to end of the body and having two sections in offset relation to each other in a lateral direction, a plurality of spaced and projecting means secured to the body to guide a current collector onto and off of the body, two guide

members pivoted to the body in aligned relation to each other and to two of the said spaced means, means associated with the guide members to pivot them in unison and out of said aligned relation when one guide member is moved, means to yieldingly hold the guide members normally in alignment, the spaced and projecting means each arranged to receive a trolley wire and detachable and pivotally mounted means at the free end of each projecting means and provided with a cam part to engage the trolley wire to hold it securely to its projecting means and having an inverted groove to receive the trolley wire and depending lips to encircle the wire.

10. A pan for a cross-over comprising a body having an elongated flat portion with a flange along each side projecting therefrom at substantially right angles to the said portion and forming a channel across the body open at the ends, the flanges being offset adjacent a mid-point to form an offset pocket or recess and a plurality of spaced and projecting arms secured to said flat portion having a portion extending along the surface of said flat portion between the flanges.

11. A pan for a cross-over comprising a body having an elongated flat portion with a flange along each side projecting therefrom at substantially right angles to the said portion, the flanges each being offset intermediate their ends to form an offset pocket or recess and a plurality of spaced and projecting elongated arms secured to the body at its ends with the oppositely disposed arms in alignment and their longitudinal axes intersecting adjacent the center of the body.

12. A pan for a cross-over comprising a body having an elongated flat portion with a flange along each side projecting therefrom at substantially right angles to the said portion, the flanges each being offset intermediate their ends to form an offset pocket or recess and a plurality of spaced and projecting elongated arms secured to the body at its ends with the oppositely disposed arms in alignment and their longitudinal axes intersecting adjacent the center of the body, the inner ends of two of the aligned arms spaced further apart than the inner ends of the other two aligned arms.

13. A pan for a cross-over comprising a body having an elongated flat portion with a flange along each side projecting therefrom at substantially right angles to the said portion, the flanges each being offset intermediate their ends to form an offset pocket or recess and a plurality of spaced and projecting elongated arms secured to the body at its ends with the oppositely disposed arms in alignment and their longitudinal axes intersecting adjacent the center of the body and a hollow pedestal projecting at right angles from the flat portion of the body adjacent

each end of the body and the longitudinal axis of each pedestal piercing the said flat portion at a point between the longitudinal axes of the arms nearest the pedestal.

- 5 14. A guide for a trolley wire intersection device comprising an elongated runner member having one end positioned in a plane obliquely disposed to the longitudinal axis of the member and the opposite end rounded, a 10 stem projecting from the member from a point adjacent the rounded end and at right angles to the said longitudinal axis upon which the guide may be pivoted and a part connecting the stem and member to offset the 15 stem from the member.
15. A guide for a trolley wire intersection device comprising an elongated runner member having one end positioned in a plane obliquely disposed to the longitudinal axis 20 of the member and the opposite end rounded, a stem projecting from the member from a point adjacent the rounded end and its axis being at right angles to the said longitudinal axis upon which the guide may be pivoted, 25 the axis of the stem being offset laterally from the axis of the elongated member.

16. A trolley device comprising a body having an elongated flat portion and a flange projecting along each side to form a trough 30 open at the ends, the sides offset adjacent their central point to form a pocket or recess, arms projecting from the ends of the body and each having a U-shaped groove to receive a trolley wire, detachable and rotatable cam 35 means at the end of each arm to hold the wire in its groove, a two-part bridging means connecting two of the oppositely disposed arms and each part pivotally mounted at their extreme ends to the body and the juxtaposed end 40 faces obliquely disposed to the longitudinal axis of the bridging member, mechanism connecting the two parts of the bridging member to pivot them in unison and the juxtaposed ends away from each other in a lateral direction, 45 means to yieldingly hold the juxtaposed ends of the bridging parts together, the mechanism connecting the bridging parts to operate them in unison being mounted on the side of the flat portion opposite to that on which 50 the bridging member is mounted and cover for the said mechanism and means to hold it in place on the body.

17. A device of the class described comprising a body with depending flanges along 55 opposite sides, means to secure spaced trolley wires to the body and guide means between the inner ends of two of the wires to guide a moving current collector from one wire to the other, the said guide means comprising 60 a pair of elongated members mounted to pivot at their ends adjacent the wires and to separate laterally at their inner ends.

18. A device of the class described comprising a body, means to secure spaced trolley 65 wires to the body and guide means be-

tween the inner ends of two of the wires to guide a moving current collector from one wire to the other, the said guide means comprising a pair of elongated members mounted to pivot at their ends adjacent the wires and to separate laterally at their inner ends. 70

19. A device of the class described comprising a body, means to secure spaced trolley wires to the body and guide means between the inner ends of two of the wires to guide a 75 moving current collector from one wire to the other, the said guide means comprising a pair of elongated members mounted to pivot at their ends adjacent the wires and to separate laterally at their inner ends, the inner ends 80 resting in a plane obliquely disposed to the longitudinal axis of the member.

20. A guide member for a trolley wire device comprising an elongated runner member having a stem upon which it pivots projecting at right angles to the longitudinal axis of the member and the axis of the stem being offset longitudinally from the said longitudinal axis. 85

In testimony whereof I affix my signature. 90
SAMUEL S. MATTHES.
